[57] **CLAIM**

The ornamental design for a self-propelled aerial work platform, as shown.

DESCRIPTION

FIG. 1 is a perspective view of a self-propelled aerial work platform embodying our new design;

FIG. 2 is a top plan view thereof;

FIG. 3 is a side elevational view thereof, taken from the right in FIG. 1;

FIG. 4 is a front elevational view thereof; and

FIG. 5 is a rear elevational view thereof.

FIG. 1

FIG. 2

FIG. 3

FIG. 4

FIG. 5
